UNITED STATES PATENT OFFICE.

EUGEN ALBERT, OF MUNICH, GERMANY, ASSIGNOR TO FERDINAND WESEL, OF NEW YORK, N. Y.

APPARATUS FOR PRODUCING MATRICES FOR ELECTROTYPE AND THE LIKE.

No. 814,927.

Specification of Letters Patent.

Patented March 13, 1906.

Application filed October 6, 1905. Serial No. 281,568.

To all whom it may concern:

Be it known that I, EUGEN ALBERT, a subject of the German Emperor, and a resident of Munich, Bavaria, Germany, have invented 5 certain new and useful Improvements in Apparatus for Producing Matrices for Electrotypes and the Like, of which the following is a specification, reference being had to the accompanying drawings, forming a part hereof.

10 In the manufacture of matrices for electrotypes it has long been recognized that if the impression could be made satisfactorily from the die or original directly upon a lead plate a great saving of time and labor would be 15 gained. The process of electrotyping as it is commonly practiced at the present time involves the preparation of a wax plate, the making of the impression in this wax plate from the die or original, the so-called "building up" of the impression, and the leading of 20 the plate before the electrolytic formation of the copper shell thereon and the removal of the wax and the substitution of a lead back therefor after the copper shell has been completed. It is at once obvious that the elimination 25 of the wax and the direct employment of a plate of lead or of some other suitable metal in the place of the wax plate would tend toward the simplification of the 30 process in a very large measure. Broadly speaking, there have been two difficulties which have heretofore stood in the way of eliminating the wax and effecting the impressions directly in lead or other soft-metal 35 plates. One of the difficulties has been that notwithstanding any degree of pressure which might be applied to press a die and a lead plate together the lead would not take the impression properly, and the other difficulty 40 was that to make relatively large impressions such an enormous amount of pressure was required to impress the lead that it was quite out of the range of even a large hydraulic or other press to effect. The first-mentioned 45 difficulty was due to the fact that when a die or original was pressed into a lead plate the portions of the plate opposite the elevations of the original had to be forced into the plate, thus involving the entire displacement of 50 such portions of the plate by compression within itself. Notwithstanding the large pressures applied to effect the impressions, which in the case of half-tones and photogravures often destroyed the fine lines of the

originals, the lead could not be made to enter and fill properly the hollows or deep portions of the originals, whereby, although the elevated portions of the originals might be impressed in the lead, yet the impressions as a whole were in most cases very unsatisfactory. In accordance with the present improvements this difficulty is overcome by employing a yielding or relatively soft layer between the lead or other substance receiving the impression and the platen of a press by 60 which it is supported or through which it receives pressure, so that the lead plate or other substance being impressed rests between this yielding layer and the die or original. In this way when the impression is being made 65 the elevated portions of the die or original force the lead or other impression-receiving substance into the yielding layer, which by reactionary pressure forces the lead or other impression-receiving substance into the deep 70 portions of the die. Furthermore, this result is effected with comparatively moderate pressures, and thus the fine lines of the originals in the cases of half-tones and photogravures and the elevated portions of the 75 dies in the case of woodcuts are uninjured. The other difficulty in effecting direct impressions upon lead, or for that matter upon wax, is due, as was stated above, to the very great pressure needed to produce relatively 80 large impressions. For instance, to effect in wax an eight by ten half-tone impression requires a pressure of about two hundred tons, and the power required to produce any impression is substantially proportional to the 85 size or extent of the impression. On this account the size or extent of the impression which could be produced heretofore even in wax was limited by the power which the press employed to make the impression could exert. 90 In accordance with the present invention the impressions are produced in sections, whereby the power required to produce the whole impression will not necessarily be of a very high degree, but will be substantially proportional to the size of the section and will have to be applied to produce the whole impression at least as many times as the particular section produced by one operation of the 95 press is contained in the whole impression. In order to effect the sectional molding of the impression, a peculiarly-formed pressure-block or platen is employed, between which 100

and the die or original the impression-receiving piece is placed, a soft layer or some equivalent device also being preferably placed between said piece and the peculiarly-formed pressure-block, as referred to above.

The improvements will be more fully described hereinafter with reference to the accompanying drawings, in which the invention is illustrated in a general way and in which a press that may be employed in carrying out the improvements is shown.

In said drawings, Figure 1 is a plan view of a number of brass rules set at different distances apart in a block. Fig. 2 is a sectional view of the same, taken on a plane indicated by the line 2 2 in Fig. 1. Fig. 3 is a sectional view of a metal matrix stamped in the ordinary way, the matrix resting down during the stamping upon a rigid surface, such as a steel platen. Fig. 4 is a similar view of a metal matrix which, during the stamping, rests down upon a yielding substance. Fig. 5 is a view in front elevation of a press, showing particularly the platens and the parts immediately adjacent thereto with a die or original, an impression-receiving piece, &c., resting between the platens. Fig. 6 is a similar view in side elevation. Fig. 7 is a view in vertical section of the lower end of the upper platen, taken on a plane indicated by the line 3 3 in Fig. 5, the difference in elevation between the successive steps in the stepped surface in this platen being exaggerated for the purpose of more clearly illustrating the same; and Fig. 8 is a plan view of the under side of the upper platen.

Reference will first be had to Figs. 1 to 4, in which there is illustrated in a general way the result obtained when a piece of metal resting down upon a hard flat surface is molded under pressure and the result obtained when a piece of metal in contact with a relatively soft layer is molded under pressure. The brass rules *a* represent the elevated portions of a die or original *b*, and the spaces between them represent the hollows, recesses, depressions, or deep parts of the die or original. When the impression-receiving piece *c* is in contact with an unyielding surface—as when resting down, for instance, upon the steel platen of a press—the elevated portions of the die or original, in the present case the brass rules, displace under great pressure (indicated at *d*, Fig. 3) portions of the impression-receiving piece, which remains perfectly flat upon the supporting-platen, Fig. 3. If the pressure be sufficiently great, the elevated portions of the die or original will sink deep enough into the impression-receiving piece to bring the portions of the impression-receiving piece well up into the hollows and depressions of the die; but, as was stated above, in the case of such impression-receiving substance as lead these great pressures usually result in the destruction of the die or original. On the other

hand, by the use of a yielding layer *e*, Fig. 4, next to the impression-receiving substance the pressure from the elevated portions of the die, in the present case from the brass rules *a*, is transmitted thereto and causes reactionary pressures in said layer, the lines of force of such reactionary pressures being illustrated in Fig. 4. Such pressures tend, as is obvious, to press the impression-receiving substance into the hollows or depressions of the die, while when the impression-receiving substance is in contact with the steel platen, as illustrated in Fig. 3, the rigidity of the steel offsets the reactionary pressures therein, and they are not, therefore, transmitted to the impression-receiving substance. Such a smooth or yielding layer *e* may comprise a number of sheets of paper or any other handy material, the thickness of this layer being about one centimeter, more or less, and depending somewhat upon the particular character of the stamping. It is always placed next to the impression-receiving piece, which may rest upon it, or vice versa, as shown in Figs. 5 to 8, where the yielding layer rests upon the impression-receiving piece. In any case the impression-receiving piece rests between the yielding layer and the die or original. When a yielding layer is not employed in the manner above described, the impression-receiving piece, as is obvious, has to be at least a little thicker than the depth of the hollows in the die—that is, than the difference in level between the elevated and depressed portions of the die, as will be clear from Fig. 3. On the other hand, with the yielding layer, as in the present case, an impression-receiving piece of a thickness about equal to one-third the difference in level between the elevations and depressions of the die is required in ordinary cases, although this depends somewhat upon the nature of the metal or other substance to be impressed. It will be clearly obvious, therefore, that much less pressure is required to form a matrix when a yielding layer is employed, as described, than has been necessary heretofore and that woodcuts, photogravures, and half-tones can be successfully handled by this method, while according to the old process the originals were generally destroyed or the impressions were unsatisfactorily made.

When a large matrix is to be made in which the impression cannot be effected satisfactorily in one operation owing to the degree of pressure required, it is, in accordance with the present invention, molded in sections. When one section or portion of the impression has been effected, the impression-receiving piece, together with the die or original, is moved so as to change its position with respect to the platens or one of them, whereby upon the next operation of the press another portion of the impression-receiving surface will be shaped or formed, and so on until the

whole surface has received the completely-formed impression. As the impressions have been produced heretofore platens of the press have been larger in area than the impressions to be produced, whereby, as will be seen, the impression was made complete in a single operation of the press. If, on the other hand, one of the platens—say the one which is in contact with the impression-receiving piece—be smaller in area than the impression to be produced, it will be clear that each time the press is operated only a portion of the whole impression will be made, and accordingly only such a proportion of the total pressure necessary for the production of the whole impression at once will be required to produce the partial impression as is represented by the ratio of the area of the partial impression to that of the complete impression. It will be at once obvious, therefore, that in effecting impressions by this sectional method no relatively large degree of power is required to be exerted by the press and that the number of impressions required by this sectional method to effect a complete impression will vary inversely with the power which the press employed is capable of exerting.

In order to prevent the deformation, spreading, giving way sidewise, &c., of the impression-receiving piece during the effecting of the sectional impressions—that is, during the operation of a platen smaller than the whole impression to be produced—the platen is constructed to exert what may be referred to as a "secondary pressure" upon the impression-receiving piece in addition to the principal or main pressure, which effects the complete molding of one of the sections of the impression. For this purpose one of the platens of the press, preferably the upper platen, is formed with an elevated portion having an area considerably less than that of the total surface of the platen, and on each side of this elevated portion the surface of the platen recedes very gradually. These receding surfaces are preferably in the form of steps, as illustrated in Figs. 7 and 8, but may be continuously smooth surfaces. If more convenient than forming each one of the platens of the press with a central elevated portion receding toward the front and back, as just described, a separate plate may be provided with such a surface, and this plate may be secured to the platen of the press.

In carrying out the invention a press of any ordinary construction may be employed. In the drawings are shown two platens *f* and *g*, one of which, preferably the upper platen, is formed with a central elevated portion *h*, which extends from one side of the platen to the other side, and receding from this central elevated portion, both toward the front and toward the rear of the platen, is a stepped surface *k*. The central elevated portion thus forms a relatively long and narrow oblong

strip, and the stepped portions on the surface of the platen form similar strips at different elevations which recede successively toward the front and the back from this central elevated portion. The width of each of the steps is largely arbitrary. In the case of impressions in lead where the width of the elevated portion is about seven and one-half centimeters the width of the steps may be about two and one-half centimeters. The difference in levels between the central elevated portion and the adjacent steps and between successive steps should be chosen so that at the moment when the central elevated portion exerts a pressure sufficient to completely mold a section the steps on either side thereof will exert a secondary pressure sufficient to prevent the deformation, spreading, giving way sidewise, &c., of the impression-receiving piece. This in the case of lead-molding necessitates a very slight difference between the central elevated portion and adjacent steps and between successive steps. The number of steps is also immaterial, one step on each side of the central elevated portion being sufficient in some cases; but it is generally most convenient to have a half-dozen or more steps on each side of the central elevated portion. The lower platen is provided with a plate *l*, 95
slidable backward and forward into the press upon the lower platen, whereby the die and the impression-receiving piece may be advanced into the press between the successive impressions, and suitable mechanism, illustrated in a general way at *m*, is provided whereby the plate *l* may be conveniently moved to the exact extent desired, which mechanism it is unnecessary to show and describe in detail.

When an impression is to be made in accordance with the improved process, the die or original from which the impression is to be taken, together with the material for receiving the impression, which is in contact with the face thereof, is placed upon the plate *l* in such a position, or the plate *l* is subsequently brought to such a position, that upon the dropping of the upper platen the central elevated portion *h* of the upper platen will be brought down, preferably over the forward end of the impression-receiving piece, which is upon the forward end of the die, form, or original from which the impression is to be made. When the requisite pressure has been applied through the platens to complete the formation of that portion of the impression which is covered by the central elevated portion of the upper platen, the upper platen is raised and the plate *l* is advanced into the machine, so that upon the next pressing a further portion of the impression will be effected. Then the upper platen is again brought down and the pressure renewed. This operation is continued until the central elevated portion of the upper

4

platen has been brought down over every part of the die or form and has thus completed the whole impression.

By employing the present improvements 5 the impressions, which are commonly made in wax at the present time from the dies or originals, may be made directly in lead, and the pressures required for the direct stamping of the lead will by no means be very 10 great. Accordingly, relatively small presses may be employed, thus not only simplifying the nature of the process, but greatly simplifying the apparatus which it is necessary to employ.

15 It will be understood that the invention is not limited to the use of lead as an impression-receiving substance, the invention having been described with specific reference to lead, for the reason that it is a metal which 20 may be conveniently employed in carrying out the improvements. Neither is the invention to be understood as limited to the electrotyping process, for it is obvious that it may be employed where any stamping is 25 to be done by the pressure method.

I claim as my invention—

1. A press having upon or integral with one of its platens a continuous and smooth elevated surface, and a receding surface fixed 30 with respect to the elevated surface.
2. A press having upon or integral with one of its platens a continuous and smooth elevated surface, and a receding surface fixed

with respect to the elevated surface upon each side of the elevated surface.

35

3. A press having upon or integral with one of its platens a continuous and smooth central elevated surface extending from side to side, a surface fixed with respect to the elevated surface and receding therefrom toward the front of the press, and a surface fixed with respect to the elevated surface and receding therefrom toward the back of the press.

40

4. A press having upon or integral with 45 one of its platens a continuous and smooth elevated surface, and a stepped surface fixed with respect to the elevated surface upon each side of the elevated surface.

50

5. A press having upon or integral with 55 one of its platens a continuous and smooth central elevated surface extending from side to side, a stepped surface fixed with respect to the elevated surface and receding therefrom toward the front of the press, and a stepped surface fixed with respect to the elevated surface and receding therefrom toward the back of the press.

In witness whereof I have hereunto signed my name in the presence of two subscribing 60 witnesses.

EUGEN ALBERT.
